UNITED STATES PATENT OFFICE.

LEE S. CHADWICK, OF SHAKER HEIGHTS VILLAGE, OHIO, ASSIGNOR TO THE CLEVELAND METAL PRODUCTS COMPANY, OF CLEVELAND, OHIO, A CORPORATION OF OHIO.

SAFETY OIL BURNER.

Application filed March 24, 1922. Serial No. 546,349.

To all whom it may concern:

Be it known that I, LEE S. CHADWICK, a citizen of the United States, residing at Shaker Heights Village, in the county of 5 Cuyahoga and State of Ohio, have invented a certain new and useful Improvement in Safety Oil Burners, of which the following is a full, clear, and exact description, reference being had to the accompanying drawings.

This invention relates to improvements in that class of oil burners wherein an air controlling member is disposed above the wick. In the operation of such burners, the air controlling member so governs and distributes the air as to supply the required amount of oxygen to the flame; to impart proper shape to the flame; and to prevent overheating of the burner parts, especially the air controlling member.

My invention is applicable to tubular types of burners wherein the air controlling member is situated within the upper end of the inner wick tubes. In such types of burners the air controlling member is ordinarily referred to as a flame spreader and the same incorporates a flange which extends out over the wick. In the following description, therefore, I shall refer to the air controlling member as a flame spreader, but without intending to limit myself to any particular construction or arrangement of parts.

In the earlier forms of tubular burners of the class to which my present improvements are applicable, an example of which is disclosed in my U. S. Letters Patent 1,251,638, dated January 1, 1918, the flame spreader is supported with its flange a fixed distance above the upper ends of the wick tubes. While the normal burning range of the wick in this form of burner precludes a position wherein the wick contacts with the flame spreader flange, it is not an uncommon occurrence for the user to turn the wick to such a height as to engage its burned end with the flange of the flame spreader, thereby creating an unsafe condition by shutting off the passage of air between the wick and the flame spreader flange and trapping within the inner wick tube combustible vapors which gradually increase in volume by their continued generation through the contact of the hot flame spreader flange with the oil saturated wick. The vapors, being com-

paratively heavy, descend within the inner wick tube where they flash and burn with the occasional result that the solder holding the burner parts together melts and the burner gives way and causes a fire. Various 60 so-called safety flame spreaders have been devised to obviate this unsafe condition but with only limited success, especially when viewed from a practical and commercial standpoint.

I have recently developed an oil burner involving an automatic wick stop which coacts with the wick raising means and prevents the wick from rising into contact with the flame spreader. The flame spreader, however, in one phase of the operation of this burner descends upon the wick, for I utilize the flame spreader for coupling the wick stop mechanism with the wick raising means. In this burner, disclosed in my co-pending application, Serial No. 528,813, filed January 12, 1922, when the wick is below burning range, the flame spreader occupies a position wherein its flange is below the upper ends of the wick tubes so that it may 80 be engaged by the wick when the latter is elevated and, through its intervention, cause the wick to lift the flame spreader. The flame spreader is connected with the wick stop mechanism in such manner as to 85 couple the stop mechanism with the wick raising means during the initial upward movement of the spreader. After this connection of the stop mechanism with the wick raising means has been effected, the flame 90 spreader is bodily lifted out of contact with the wick by the wick raising means. However, there is an appreciable interval during which the flange of the flame spreader is in contact with the wick, and upon turning the 95 wick down below burning range in order to extinguish the flame it sometimes happens, though very seldom, that the flange of the flame spreader is left resting upon the wick. Why it so infrequently occurs is readily ex- 100 plained by the fact that unless the wick is turned low enough to actually withdraw from the flange of the flame spreader, the flame is not completely extinguished, and it is only through extreme carelessness or inattention on the part of the user that the burner is left in such a condition. When this unusual situation does occur, however, particularly in large burners, if it were not

for the provisions of my present invention, 110

the same unsafe condition might exist here as prevails in the previously discussed class of burners when the wick is raised into actual contact with the flange of the flame spreader.

The fundamental purpose of my present invention, therefore, is to provide an air controlling member for burners of the class described incorporating means for preventing accumulation of vapors within the inner wick tube or beneath the air controlling member when said member is in contact with the wick, and which will not interfere with the normal operation of the burner or in any way impair the character of the flame produced thereby.

Further objects are to provide a simple and inexpensive construction through which the foregoing purpose is effectually attained, and which operates with a high degree of efficiency and, by reason of its peculiar control of the air drafts directed in proximity to the flame, maintains the parts adjacent the flame at a comparatively low temperature.

In the accompanying drawings, Fig. 1 is a fragmentary sectional view through that type of burner wherein the air controlling member or flame spreader is utilized for coupling wick stop mechanism with the wick raising means and showing said member or spreader in the position it occupies when the wick is below burning range; Fig. 2 is a similar view showing the air controlling member or flame spreader elevated and the wick at its maximum height; Fig. 3 shows certain of the parts of Fig. 2 more or less diagrammatically and on a considerably enlarged scale; and Fig. 4 is a fragmentary sectional side elevation of the type of burner wherein the air controlling member or flame spreader is supported with its flange a fixed distance above the tops of the wick tubes, the air controlling member or flame spreader embodying my present invention.

As is well known, burners of the class in connection with which my improvements are herein illustrated, consist of inner and outer wick tubes 1 and 2 between which the wick 3 is guided, it being recalled that the wick tubes are connected at their lower ends with a liquid tight joint so as to effectually close the wick space at all points except between their upper ends and at a point near their lower ends where a suitable fitting is applied to one of the tubes and through which communication is established between the wick space and a source of fuel supply.

With respect to the form of burner illustrated in Figs. 1, 2 and 3, the same incorporates a wick stop mechanism that is fully disclosed in my copending application hereinbefore referred to. 5 is a spanner which

the inner wick tube and from which depends a frame 6 that carries, at its lower end, the mechanism through which the spanner is coupled with the wick raising means in the manner clearly set forth in said application. 70 The flame spreader which is designated generally by the numeral 10 reposes within the upper end of the inner wick tube 1 and rests upon the spanner 5 and is adapted to be locked thereto by tumblers 11 75 that are pivoted at 12 to the frame 6 when said tumblers are forced apart by the insertion between their adjacent edges of a locking pin 13 that is movably carried by the spanner and which acts to project and positively retain the keepers 14 of the tumblers over the shoulder 15 of the lock 16 which constitutes a part of the flame spreader. This flame spreader latch, in substantially identical form with that shown here, and in other forms suitable to the present purpose, is disclosed in my copending application Serial No. 528,833, filed January 12, 1922, and as it constitutes no part of my present invention, further description is deemed unnecessary.

Fig. 1 shows the wick 3 below burning range, and the flame spreader in the position it would occupy under such conditions. Fig. 2 shows the wick raised, and the flame spreader elevated to the position wherein it functions purely as an air controlling member.

The flame spreader comprises, besides the before mentioned lock 16, a top 20 which is shown as connected adjacent its center with the top of the lock 16; a tube 21 which depends from the top 20; a flange 22 which is carried by the tube 21 and extends outwardly beneath the peripheral portion of the top 20 and at its outer edge is turned abruptly downwardly; a flange skirt 23 which is situated immediately below the flange 22 and is curved gradually downwardly toward, but is spaced a suitable distance inwardly from the lower edge of the flange; and a body 24 which consists of a substantially cylindrical wall made up of interfitting parts 25 and 26, the latter being drawn inwardly at its lower end and connected to the tube 21 at 27. The tube 21 has a series of comparatively large openings 30 through which its interior communicates with the space between the flange 22 and the peripheral portion of the top 20, 120 and a second series of similar openings 31 which open into the space enclosed by the body 24. The peripheral portion of the top 20 has perforations 32 and 33, its central portion perforations 34, and the body has a 125 series of perforations 35 in its cylindrical wall and perforations 36 in its bottom wall. My improvements consist essentially in providing the flange 22 of the flame spreader with air passageways adjacent its periph- 130

ery which, in the present instance, consist of perforations 38; and also in placing the skirt 23 beneath the flange and so disposing it with respect thereto as to form therewith 5 an annular pocket 40.

The arrows in Fig. 3 indicate the air drafts through the spreader, and attention is called particularly to the current of air which sweeps out beneath the skirt 23 and 10 under the edge of the flange 22, carrying the products of combustion outwardly away from the spreader parts, thus maintaining them at a comparatively low temperature, while imparting proper shape to the flame 15 and supplying the required oxygen to promote combustion.

It may be stated also that the air passing up through the perforations of the top 20 prevents the flame from converging to too great an extent as it rises about the spreader. 25 The air currents which pass through and about the body 24 prevent vapors from falling into the space between the body and the inner wick tube and from condensing on the body. When observing the normal operation of the burner it is indiscernible that any air passes through the perforations 38 of the flange 22, the skirt 23 apparently deflecting practically all of the air beneath the lower 30 edge of the flange. However, when the parts are in the condition illustrated in Fig. 1, with the flange 22 resting upon the burned end of the wick, the skirt 23 tends to trap the vapors that are generated by contact of 35 the hot flange with the saturated wick within the pocket 40 from which they readily escape through the perforations 38. It will be seen, therefore, that the skirt 23 has the two-fold purpose of directing the air beneath the flange 22, when the burner is in 40 operation, and of preventing the vapors from dropping down into the wick tube, when the flange is in contact with the wick. The upper end of the inner wick tube also 45 effectually contributes to the latter result.

In the form of burner illustrated in Fig. 4 a spanner 45 is secured within the inner wick tube 1 adjacent its upper end. The flame spreader shown in this burner comprises a tube 46, to the upper end of which is applied a top 47. A flange 48, corresponding to the flange 22 of the previous form, is carried by and extends outwardly from the tube 46 a suitable distance below the top 47, and a skirt 49 is situated immediately below the flange 48 and has its outer edge directed downwardly toward but spaced a suitable distance from the edge of the flange 48. The body of the flame spreader comprises a cylindrical wall 50 and a bottom wall 51 which extends inwardly and downwardly from the cylindrical wall and has its inner edge secured to the tube 46. The tube is provided with openings 52 through which its interior 60 communicates with the space between the

top 47 and the flange 48, and with openings 53 through which its interior communicates with the space enclosed by the body of the spreader. A frusto-conical deflector 55 extends outwardly and downwardly from the tube 46 immediately above the openings 53. The lower end of the tube 46 terminates in a series of locking segments 56 each of which has a shoulder 57 that is adapted to lock beneath a pin 58 which extends inwardly from the neck 59 of the spanner 45.

In this form of the burner, the flame spreader is supported with its flange 48 a fixed distance above the upper ends of the wick tubes, and in case the wick is turned so high as to engage the flange 48, the vapors generated under these conditions beneath the flange will be trapped in the space between the skirt 49 and flange 48 and escape through perforations 60 in the flange, to mingle and burn with those rising from the outer exposed surface of the wick. So far as this phase of the operation is concerned, the effect would be substantially the same if the skirt 49 were omitted. The essential duty of the skirt is to direct the air downwardly beneath the flange 48 during the normal operation of the burner.

Referring again to the burner shown in Figs. 1 to 3, it might be well to call attention to a situation unlikely but possible of happening in the use of the burner. Let it be supposed that, upon putting a new wick in the burner, or, with the flame spreader removed and the wick turned up to or above the normal operating position of the flame spreader flange, the flame spreader were set into the burner with its flange resting upon the wick and the wick lighted (either before or after the flame spreader was emplaced), the vapors generated beneath the flange would escape through the perforations 38 and burn with those rising from the outer exposed part of the wick. The burner could operate indefinitely under these conditions with only the effect of producing a relatively poor flame of comparatively low efficiency.

Having thus described my invention, what I claim is:

1. In a burner of the class set forth, an air controlling member having a part where-with the burned end of the wick may contact under certain conditions though normally out of contact therewith, said part having air passageways through which vapors generated in the region of contact between the wick and said part may escape in close proximity to the wick.

2. In a burner of the class set forth, an air controlling member having a part where-with the burned end of the wick may contact under certain conditions, said part having passageways through which vapors generated by contact of the wick with said part may escape in close proximity to the wick,

and an element in juxtaposition to said part and serving to retain the vapors between it and said part, said element, when the burner is in normal operation, serving to direct air beneath said part.

3. In a burner of the character set forth, an air controlling member having a part wherewith the burned end of the wick may contact under certain conditions, said part 10 having perforations through which vapors generated in the region of contact between the wick and part may escape, and a deflector spaced from said part and enclosing with said part a pocket for the vapors, the 15 deflector, during the normal operation of the burner, serving to direct air beneath said part.

4. In a burner of the character set forth, an air controlling member having a part 20 extending over and downwardly toward the wick and with the edge whereof the wick may contact under certain conditions, said part having a series of perforations adjacent its edge, an element spaced from said 25 part and enclosing with said part a pocket for vapors generated in the region of contact between the wick and said part and from which pocket the vapors may escape through the aforesaid perforations, said element, during the normal operation of the 30 burner, serving to direct air beneath the edge of the part wherewith the wick contacts.

5. In a burner comprising wick tubes between which the wick is guided, a flame 35 spreader supported within the upper end of the inner wick tube, the flame spreader having a flange extending outwardly and over the space between the tubes and with the 40 edge whereof the burned end of the wick may contact under certain conditions, the flange having a series of perforations adjacent its edge.

6. In a burner comprising wick tubes between which the wick is guided, a flame 45 spreader supported within the upper end of the inner wick tube, the flame spreader having a flange extending outwardly and over the space between the tubes and with the 50 edge whereof the burned end of the wick may contact under certain conditions, the flange having a series of perforations adjacent its edge, and a skirt extending outwardly and downwardly beneath the flange 55 to enclose therewith a pocket for trapping vapors generated in the region of contact between the wick and flange and from which the vapors may escape through the aforesaid perforations, the skirt serving, during 60 the normal operation of the burner, to deflect air outwardly beneath the flange.

7. In a burner comprising wick tubes between which the wick is guided, a flame 65 spreader supported within the upper end of the inner wick tube, the flame spreader hav-

ing a flange extending outwardly over and downwardly toward the wick so that its edge may be engaged by the burned end of the wick under certain conditions, the flange having a series of perforations adjacent its 70 edge, and a skirt immediately below the flange and extending outwardly and downwardly toward the edge of the flange and enclosing with the flange a pocket in which vapors generated in the region of contact between the wick and flange may be trapped and from which the vapors may escape through said perforations, the skirt serving during the normal operation of the burner to direct air downwardly beneath the flange. 75

8. In a burner incorporating wick tubes between which the wick is guided, a flame spreader supported within the upper end of the inner wick tube and comprising a tubular member, a top applied thereto, the peripheral portion of the top extending outwardly over the space between the wick tubes, a flange extending outwardly from the tubular member beneath the peripheral portion of the top and having its edge portion directed downwardly for contact with the wick under certain conditions, the downwardly turned portion of the flange being provided with a series of perforations, a skirt situated immediately below the flange 85 and extending outwardly and downwardly toward the edge of the flange and enclosing with the flange a pocket in which vapors generated at the region of contact between the wick and flange are trapped and from 90 which the vapors may escape through said perforations, a body portion spaced below the skirt and secured to the tubular member, the tubular member having openings through which its interior communicates with the space between the peripheral portion of the top and the flange and the space 95 between the skirt and the body, the body and top having perforations suitably distributed to afford a proper distribution of air. 100

9. In a burner incorporating wick tubes between which the wick is guided, a flame spreader supported within the upper end of the inner wick tube and comprising a tubular member, a top applied thereto, the peripheral portion of the top extending outwardly over the space between the wick tubes, and a flange extending outwardly from the tubular member beneath the peripheral portion of the top and having its 115 edge portion directed downwardly for contact with the wick under certain conditions, the downwardly turned portion of the flange being provided with a series of perforations. 120

10. In a burner of the character set forth, in combination with the wick guide, an air controlling member movably supported with a part thereof disposed above the wick and wherewith the wick is capable of engagement when the top of the wick is below the 130

top of the wick guide, the top of the wick, the guide and said member under such conditions being so disposed with respect to each other as to form a pocket wherein vapors generated by the engagement of said part with the wick are trapped, said part having outlet passageways for the vapor.

11. In a burner of the character set forth, in combination with the wick tubes, an air 10 controlling member movably supported in operative relation to the wick tubes and having a flange disposed over the space between the tubes and wherewith the wick is capable

of engagement when the flange is below the plane of the tops of the tubes, the top of the wick, the flange, and the top of one of the wick tubes under such conditions being so disposed with respect to each other as to form a pocket wherein vapors generated by the engagement of the flange with the wick 20 are trapped, the flange having a series of perforations through which the vapors may escape.

In testimony whereof, I hereunto affix my signature.

LEE S. CHADWICK.
